UNITED STATES PATENT OFFICE.

FRANK M. ASHLEY, OF BROOKLYN, NEW YORK, ASSIGNOR TO GENERAL ELECTRIC COMPANY, A CORPORATION OF NEW YORK.

ELECTRIC RAILWAY.

SPECIFICATION forming part of Letters Patent No. 688,572, dated December 10, 1901.

Application filed February 26, 1898. Serial No. 671,789. (No model.)

To all whom it may concern:

Be it known that I, FRANK M. ASHLEY, a citizen of the United States, residing at Brooklyn, county of Kings, State of New York, have 5 invented certain new and useful Improvements in Electric Railways, of which the following is a specification.

This invention relates to electric railways and has special reference to conduit systems 10 employing a main conductor and one or more sectional or working conductors.

The object of the invention is to provide a system of this character in which the escape 15 of current by leakage is reduced to the minimum and in which both the main and the return current passes through the rails or a portion of them without exposing persons or animals to the danger of a shock either by contact with the rail or by an accidental cross- 20 circuit from one rail to the other.

The invention comprehends the details of construction which will be hereinafter fully described, and pointed out in the claims.

Referring to the accompanying drawings, 25 Figure 1 represents the plan of a portion of a roadway with the covering of the conduit removed. Fig. 2 is a cross-section of the same, showing also certain devices carried by the car. Fig. 3 is a detail of an insulated joint 30 in the rails. Fig. 4 is a longitudinal section of the conduit and the traveling switch moving therein. Fig. 5 is a conventional view of the various conductors and electric circuits. Fig. 6 is a plan of the conduit at a crossing 35 with the covers removed. Fig. 7 is a longitudinal section of the conduit at a crossing; and Fig. 8 is a sectional view of the conduit, showing a modified form of traveling switch in section.

40 Referring to the drawings by letter, A and A' represent the two rails of a track upon which the car is run. The wheels of the car are represented by A². In Fig. 1 the car also carries a small truck a, which is located between the two pairs of main wheels. This truck is provided on each side with two small wheels a', which also run upon the same rails. The truck supports a block of soft iron b, which is supported directly over the center 45 of the conduit located between the rails. The wheels of this truck are insulated in any well-

known manner from the frame of the truck; but their function is to make electrical contact with the main rails of the track, and they are therefore connected with suitable conductors in the circuit in the manner herein- 55 after described. The main rails of the track are each divided into short sections, which are insulated from each other and are made, preferably, less than the length of a car. The 60 sections of the two rails are located directly opposite each other, so that the wheels on the opposite sides of the truck will make and break contact with their respective sections simultaneously. 65

C represents the conduit, provided with suitable supports or ties c, to which are secured four rails arranged throughout the conduit parallel to each other. The two outer rails c' c² are divided into sections of exactly 70 the same length and location as the sections of the main rails of the track upon which the car runs. The two inner rails c³ c⁴ are both continuous. They constitute the main conductors of the system and carry the current 75 from and to the generator, which is represented by G. The sections of the outer rails c' c² are respectively connected with the corresponding sections of the main rails of the track by branch conductors c⁵. In the conduit is located a traveling switch D for each 80 car. This consists of a soft-iron body wound with a coil of wire d and supported upon wheels d', which run upon the outer rails c' c². These wheels are insulated from the body 85 of the switch and are not intended to be a part of the circuit. Underneath the switch, between the wheels, is supported a truck carrying four pair of wheels, which bear, respectively, upon the four rails over which the 90 switch passes. The two wheels d² are insulated from the wheels d³, while the two wheels d⁴ are respectively connected with the two wheels d⁵. The truck is insulated from the body of the switch, as shown in Fig. 4. 95

The electric circuits are as follows: from the generator G, along the continuous rail c³ to the wheels d³, through the coil d on the switch to the wheels d², thence by the sectional rails c' and the branches c⁵ to the main sec- 100 tional rail A, thence to the wheels a', through the motor on the car to the other wheels a', to

rail A', branches c^5 , sectional rail c^2 , wheels d^4 , wheels d^5 , and back to the generator by the continuous rail c^4 . It will be seen, therefore, that the main circuit includes the coil 5 on the traveling switch and the motor on the car. As the car moves along over the track, the attraction which exists between the traveling switch and the soft-iron body b , which constitutes the armature of the magnet, will 10 cause the magnet to travel along upon the rails in the conduit in unison with the car. As the switch moves along it will successively switch the current from the main conductors c^3 c^4 to the sectional conductors in the conduit 15 and on the surface of the roadway.

I am aware that it has been proposed to construct a system in which one of the main rails of the track is continuous and the other in sections insulated from each other; but in 20 such systems water will sometimes collect and connect a number of adjacent sections together, and then if the two rails are connected together by a conductor there will be a short-circuiting of the system at that point, 25 and it is possible for persons or animals to receive a shock in this manner. With the present system this would not be likely to occur, as it is necessary that the sections on both sides shall be connected continuously 30 by water at points directly opposite each other in order to obtain the short circuit referred to.

In Fig. 6 I have shown a plan for crossing two conduits without breaking the circuits. 35 In one of them the rails are continued straight through, while in the other the rails dip beneath the continuous rails. This is shown more particularly in Fig. 7. The continuous rails i rest in the U-shaped recesses formed 40 by the dipping parts i' of the other conductors, and insulating matter is interposed between the two conductors where they cross in this way. The surfaces of both conductors are flush with each other, thus permitting 45 the traveling switch to pass over without jolting. In Fig. 7 is also shown a modification in the form of the switch or more particularly in the manner of applying the coil. The magnet-core is horizontal and is separated 50 from the frame of the switch. It is provided with two pole-pieces j , located at its opposite ends. It is also mounted so as to be movable to a limited extent in a vertical direction. The under sides of the pole-pieces 55 are cut away on a curve, and when the magnet is not energized these curved pieces rest upon cylinders g' , carried by the axles of the switch shown in Fig. 8, thereby forming a brake to prevent the movement of the switch 60 on an inclined portion of the road or by its own momentum after the current is turned off. In action the attraction between the magnet and the armature carried by the car causes the core with its pole-pieces to lift 65 slightly, and thus free the wheels and permit the switch to move along with the car.

In another application filed by me Decem-

ber 23, 1892, Serial No. 456,138, I have shown a traveling switch wound with a coil acting in combination with an electromagnet carried by a car. I do not claim herein that particular combination, but the specific combination of a traveling electromagnet in a conduit and an armature carried by the car I do claim herein. 70

Having thus described my invention, I claim—

1. In an electric railway, the combination, with the feeder, of a magnet-coil connected therewith, a sectional service-conductor, a 80 traveling switch on which said coil is mounted, the switch being adapted to connect the coil with the successive sections of the service-conductor, and an armature carried by the car and adapted to coöperate with the coil. 85

2. In an electric-railway system, the combination of the two rails of a track divided into insulated sections, a conduit located adjacent thereto, four connecting-rails located in said conduit, two of which are continuous and two sectional—the sectional rails being respectively connected with the sectional track-rails and a traveling switching apparatus making contact with said four rails to switch the current into the track-sections 95 successively, substantially as described.

3. In an electric-railway system, two track-rails, both divided into insulated sections, in combination with two continuous conductors isolated from the street and switching devices controlled by the moving car to successively energize the corresponding sections of the two track-rails, substantially as described. 100

4. In an electric-railway system, two track-rails, both divided into insulated sections, in combination with two isolated sectional conductors, the sections of which correspond to those of the track-rails, two isolated continuous conductors, and switching devices controlled by the moving car to successively 105 energize the corresponding sections of the four sectional conductors, substantially as described. 110

5. In an electric-railway system, two track-rails, both divided into insulated sections, in combination with two isolated sectional conductors, the sections of which correspond to those of the track-rails, two isolated continuous conductors, and a traveling switching apparatus moving along the roadway in contact with said four isolated conductors, an electrically-propelled car moving upon the track-rails and means for causing the switching apparatus to move along with the car for the purpose set forth. 125

6. In an electric-railway system, the combination of two sets of conductors crossing each other and serving as rails for a traveling vehicle, one set of conductors having dipped or U-shaped portions occupied by the conductors of the other set, the crossing conductors being insulated from each other, substantially as described. 130

7. In an electric-railway system, the com-

bination with a conducting-rail, of a second conducting-rail extending in the same plane, at a different angle, and having spaces for the reception of the first rail.

- 5 8. A traveling switch for an electric-railway system, consisting of a frame mounted on wheels, an electromagnet member loosely mounted therein and having curved recesses, and a correspondingly - curved surface for 10 said recesses on the axles of said contact-wheels.
9. A switch for an electric-railway system, consisting of a slotted frame mounted upon contact-wheels, a horizontally-arranged electromagnet - core having pole-pieces at each 15 end adapted to reciprocate in the slots of the frame, said pole-pieces having lower curved recesses, and correspondingly-curved members on the wheel-axles.
- 20 10. In an electric-railway system, the combination with two sectional track-rails constituting the positive and negative service-conductors, of two continuous isolated main conductors, and an independent switch traveling with the car to connect each continuous 25 conductor with the successive sections of the track-rails.

11. In an electric-railway system, the combination with two sectional track-rails, of two 30 continuous isolated conductors, and a switch mechanically independent of the car but adapted to travel therewith to successively energize the track-rail sections.

12. In an electric-railway system, the combination with two sectional track-rails, of two 35 sectional conductors whose sections are electrically connected to the respective sections of the track - rails, two isolated continuous conductors, and a switch controlled by the 40 car and adapted to connect the continuous

conductors with the successive sections of the sectional conductors.

13. A traveling switch for an electric-railway system adapted to electrically engage the isolated positive and negative line conductors to connect said conductors with two lines of sectional conductors respectively which have connections with the motor on the car. 45

14. In an electric railway, the combination, with the positive and negative continuous 50 main conductors, of positive and negative sectional service-conductors serving as track-rails, and a traveling switch adapted to engage said main conductors to connect the mains with the sections of positive and negative 55 sectional rails respectively as the car proceeds, whereby current is conducted to and from the car-motors through the car-wheels.

15. A switch for an electric-railway system adapted to travel with a car, but mechanically independent thereof, and adapted to connect the isolated positive and negative line conductors with positive and negative sectional conductors respectively, which have 60 connections with the car-motor. 65

16. A traveling switch for an electric-railway system mechanically independent of the car, and adapted to connect the positive and negative isolated line conductors with positive and negative sectional conductors respectively, which have 70 connections with the car-motor, and electromagnetic means for causing said switch to travel in parallelism with the car.

In witness whereof I have hereunto set my 75 hand, this 13th day of November, 1897.

FRANK M. ASHLEY.
